SNOWPLOW

George C. Soule and John B. Woodbury, South Portland, Maine, assignors to Maine Steel Products Company, Portland, Maine, a Corporation of Maine

Application August 1, 1930. Serial No. 472,238

13 Claims. (Cl. 37—44)

On account of the extensive and increasing use of the motorized vehicle during all seasons of the year it has become imperative, throughout the snow belt in the northern portions of the 5 country, to keep the highways clear of snow during the winter months.

On occasions when there is but a light or moderately heavy fall of snow it is of particular advantage to employ snow-removing apparatus 10 which is extremely mobile or adaptable of rapid locomotion over the roads, and for this purpose a light type of snow plow propelled by a motor truck offers a preferable combination for the reason that a greater stretch of road-bed 15 can be cleared in a given time and at a greatly reduced expense than is possible with the more cumbersome heavy tractor-driven piece of apparatus.

Truck plows have previously been constructed 20 on one of three principles; either to push from the front axle of the truck, or to push from the chassis frame back of the front wheels through push members which pass under the front axle, or to push from the front end of the chassis 25 frame with balancing members rigid with the nose of the plow passing under the front axle and spaced from the chassis back of the front wheels by spacing members which cause the plow to maintain its level position while pushed from 30 above its center of gravity.

In the first instance no part of the plow comes back of the front wheels with the result that there is nothing except the body or chassis of the truck to support the thrust of the rear end 35 of the wing. The variability of design of bodies makes any attachment to them for supporting the thrust of the wing complex and correspondingly liable to breakage and field trouble. Supporting the thrust of the rear end of the wing 40 from the chassis means that the elevation of the wing is limited because if lifted much above the level of the chassis frame the wing tends to fold in from snow pressure while undue strains on the chassis frame result from lowering the 45 wing much below it due to the angle of the push arm.

In the second and third type instanced above, the distance between the front axle and the ground is definitely limited. Members strong 50 enough either to push or to balance must in order to secure strength take up appreciable space below the level of the front axle.

We have previously employed elements which 55 we designate as "balance bars", the function of which is to hold the mold boards on a substantially even keel, or in other words, to prevent their buckling or jack-knifing which, in the snow plow as ordinarily constructed is occasioned by the nose of the plow riding an obstacle or by its 60 falling into a depression in the road bed.

By employing these balance bars the mold boards rise and fall in an arc struck from a point coincident with that from which the outer ends of the bars swing; and as they extend rearwardly for a considerable distance the radius of 65 this arc is long and the surfaces of the mold boards present, for all intents and purposes, a constant angle to the snow when the plow is in service. They, furthermore, hold the mold boards more rigidly to the work when plowing and prevent much of the side slat or "shimmying" characteristic of ordinary plow construction. The insertion of a member of substantial size underneath the front axle tends to cause trouble for 70 two reasons. First, it limits the lift of the nose 75 of the plow because the nose can only be lifted until the members underneath the front axle contact with the axle and as they must be some distance off the ground to prevent wearing by friction with the ground their movement is 80 comparatively limited. Second, when deep snow is encountered and truck and plow penetrate until stopped by the resistance of the snow the front 85 wheels have a tendency to sink in when attempting to back out. As soon as they sink in the front 90 axle being lowered thereby comes in contact with balancing or push members underneath it and the front end of the truck becomes supported on the balancing members and by the full area of the plow resting on the snow which usually means 95 great trouble in shoveling out under the plow or filling in under the wheels in order to back out and start again.

This is peculiarly apt to happen in trucks which 95 drive on all four wheels as the power in the front wheels tends to spin them and frequently only two or three revolutions are necessary to make the chassis dig a deep enough hole so that not only is all front wheel traction lost, but the rear 100 wheels are faced with the duty of hauling out not only the front wheels but the front wheels riding on the inner surface of the plow on the snow.

To obviate the difficulty just recited, we have, 105 in our present invention, applied balance bars to the outer portions of the snow plow where they serve as the lateral members of the plow frame; and by extending them for a considerable distance into the space between the mold boards—to which they are rigidly secured, and rearwardly where they are joined by a substantially 110 constructed cross member, a more stable and effective control over the movements of the forward end of the snow plow is procured.

These outside side beams furnish substantial 115 means of supporting the thrust of the rear end of the wing lacking in the first type of plow instanced above, together with the means of pushing the balancing members, as in the second and third types instanced above, without any member under the front axle so that the plow is free to 120

lift regardless of the height of the front axle and so that the front wheels of the truck may dig in without throwing snow in the way of the truck on the plow.

Proper facilities are also furnished by which various adjustments may be had in the suspending elements so that the apparatus is applicable for attaching to the frame of various types and sizes of motor trucks with the least amount of effort required in making connection of the parts.

To obtain a clearer understanding of the import of our invention reference should be had to the description found in the following specification when taken in connection with the accompanying drawings in which:

Fig. 1 is a plan view of a snow plow equipped with apparatus according to our present invention.

Fig. 2 is a rear end elevation of the apparatus.

Fig. 3 is a side elevation of the parts shown in Fig. 1.

Fig. 4 is a perspective view showing the parts involved in the suspension of the balance bars from the frame of the motor truck, and

Fig. 5 is a fragmentary plan view of an alternative method of motivating the snow plow.

Referring to the drawings, 1 represents the mold boards of the snow plow, 2 the wings, 3 the shoes and 4 the superstructure in general, the various devices for hoisting and operating the plow not being shown.

Fixed to each of the mold boards 1 is a beam 5, the forward end extending into the space between the former and secured thereto at a short distance above the bottom of the plow. The rearward portion of the beam 5 is slightly inclined upwardly as the rear end is approached, as seen in Fig. 3.

These beams, one on each side of the plow, constitute the balance bars for the mold boards and also serve as the lower lateral members or sills of the plow.

When the plow is in service the truck is disposed between the two balance bars and its frame 6 (the only part of the truck shown) makes connection with a cross member 7 which operates in a vertical slot 8. This permits of more or less yieldability, vertically, between the truck frame and the mold boards.

In Fig. 4 is shown the arrangement of the parts employed to suspend the rearward ends of the balance bars. A T-bar 9 having holes 10 in its inner leg is secured preferably by electric welding to the inner side of each balance bar and a transverse member 11 having yoked ends 12 makes connection with the two plates by means of the pins 13 which may operate in either one of the holes 10 a plurality of which latter are provided for the purpose of locating the member 11 in that set of holes which best accommodates itself to the height of the particular truck frame being employed with the snow plow.

As best shown in Figs. 2 and 4, the transverse member 11 is hollow and the yokes 12 are adjustable in the ends thereof, so as to accommodate the balance bars to truck frames of varying widths, the endwise adjustment of the yokes being held in any suitable manner, as by the pins 12¹.

A short section of channel 14 is secured to each of the truck frame members 6 by any approved method, preferably by the use of U-bolts 15 which provides for longitudinal adjustment 75 of the channels along the frames.

To the legs of the channel is welded a flat bar 16 pivotally mounted on which over the bolt 17 is a link 18 having at its lower end a hole 19 through which operates the transverse member 11.

It will be seen that the member 11 acts to tie the two balance bars together transversely of the snow plow structure and that the two links 18 revoluble on the member 11 suspend the latter from the two respective frame members of the truck.

To maintain centralization of the truck within the space between the balance bars, turnbuckles 20 associated with links 21 are employed, the yoked ends 22 and 23 of each turnbuckle being secured to the leg 16¹ of the bar 16 and the lug 24, respectively, the lug 24 being welded to the balance bar.

We may elect to propel the snow plow by a method illustrated in Fig. 5, in which case the forward end of the truck is not directly connected for driving purposes to the mold board structure, but chains 25 are employed which operate from the truck frames to the transverse member 11, which, in this instance becomes a draw-bar as well as a transverse cross-tie between the balance bar units.

Fig. 5 also shows the inner end of the wing push-arm 26 arranged on the slide 27 so that vertical movement of the inner end of the arm 105 may be provided on the upright member 4 of the superstructure of the plow. This permits of the lateral thrust of the wing being taken by the push-arm normally, and is useful when making shoulders on high banks of snow.

The truck now becomes an independent factor in the complete equipment, serving only as a propelling agent. The wings being wholly detached from any connection with the truck operate from the superstructure elements which, in turn, are supported by the balance bars, an arrangement peculiarly advantageous with respect to installation and operation and particularly so in the matter of expeditious assembly of truck and plow.

The apparatus herein set forth provides a strong, stable and efficiently operating combination both as to the nose and the lateral wing pressures.

What we therefore claim and desire to secure by Letters Patent is:—

1. In a snow plow equipment, a plow nose, means for loosely connecting the nose with a truck frame end, rearwardly extending bars laterally of the plow nose, attaching links, means for pivotally mounting said links on the truck frame sides, a transverse member pivotally engaged by said links, and a connection between the transverse member and the rearwardly extending bars.

2. In a snow plow equipment, a plow nose, means for loosely connecting the nose with a truck frame end, rearwardly extending bars on the plow nose and adapted to be disposed laterally of a truck frame, lateral attaching links, means for pivotally mounting said links on the truck frame, a transverse member pivotally engaged by said links, and connection between the transverse member and the rearwardly extending bars.

3. In a snow plow equipment, a plow nose, means for loosely connecting the nose with a truck frame end, rearwardly extending bars on the plow nose and adapted to be disposed laterally of a truck frame, lateral attaching links, a longitudinally extensible transverse member piv-

- totally engaged by said links, and connection between the transverse member and the rearwardly extending bars.
4. In a snow plow equipment, a plow nose, means for loosely connecting the nose with a truck frame end, rearwardly extending bars on the plow nose and adapted to be disposed laterally of a truck frame, lateral attaching links, means for pivotally mounting said links on the truck frame, a longitudinally extensible transverse member pivotally engaged by said links, and connection between the transverse member and the rearwardly extending bars. 80
5. In a snow plow equipment, a plow nose, means for loosely connecting the nose with a truck frame end, rearwardly extending bars laterally of the plow nose, and disposable laterally of a truck connected to said nose, bar attaching links, means for pivotally mounting said links on the truck frame, and connection between the links and the rearwardly extending bars. 85
6. In a snow plow equipment, a plow nose, means for loosely connecting the nose with the forward ends of a truck frame, shoes at the rear of the nose, balance bars on the nose and extending rearwardly of the nose shoes, bar connections adapted to be pivotally mounted on a truck frame at one end, and a pivotal connection between the other ends and the nose bars. 90
7. In a snow plow equipment, a plow nose, means for loosely connecting the nose with the forward ends of a truck frame, shoes at the rear of the nose, balance bars on the nose and extending rearwardly of the nose shoes, bar connections adapted to be pivotally mounted on a truck frame at one end, and a pivotal connection between the other ends and the nose bars, and adjustable connections between the nose bars and connectable with the truck for laterally centering them relative thereto. 95
8. In a snow plow equipment, a plow nose, means for loosely connecting the nose with the forward ends of a truck frame, shoes at the rear of the nose, balance bars on the nose and extending rearwardly of the nose shoes, bar connections adapted to be pivotally mounted on a truck frame at one end, and a pivotal connection between the other ends and the nose bars, and adjustable flexible connections between the nose bars and connectable with the truck for laterally centering them relative thereto. 100
9. In a snow plow, the combination with a plow nose, and a truck frame connected at its forward end with said nose, of a pair of spaced balance bars extending rearwardly from said nose outside of the line of the side members of the truck frame and defining lateral frame members disposed outwardly of the truck wheels and within which the truck frame is enclosed, and means for supporting said balance bars from the rear end of said truck frame, comprising a transverse member pivotally secured at its ends to said balance bars, and a pair of supporting members carrying said transverse member and pivotally secured at their upper ends to said truck frame. 105
10. In a snow plow, the combination with a plow nose, and a truck frame connected at its forward end with said nose, of a pair of spaced balance bars extending rearwardly from said nose outside of the line of the side members of the truck frame and defining lateral frame members disposed outwardly of the truck wheels and within which the truck frame is enclosed, means for 110
- adjustably supporting said balance bars from the rear end of said truck frame, and means for maintaining centralization of said truck frame within the space between said bars, said centralization maintaining means including longitudinally extensible laterally disposed links pivotally fastened at their inner and outer ends to said truck frame and balance bars, respectively, and said supporting means including a transverse member pivotally secured at its ends to said balance bars, and a pair of supporting members carrying said transverse member and pivotally secured at their upper ends to said truck frame. 115
11. In a snow plow, the combination with a plow nose and a truck frame connected at its forward end with said plow nose, of a pair of spaced balance bars extending rearwardly from said plow nose outside of the line of the side members of the truck frame and defining lateral frame members disposed outwardly of the truck wheels and within which the truck frame is adapted to be enclosed, a pair of vertically disposed anchoring members carried by said balance bars, a cross member adjustably attachable to said anchoring members at various selected heights vertically thereof, a pair of vertically disposed attaching members mounted on the truck frame, and a pair of suspension members pivoted at their upper ends to said attaching members 120 of the truck frame and at their lower ends carrying said cross member. 125
12. In a snow plow, the combination with a plow nose and a truck frame connected at its forward end with said plow nose, of a pair of spaced balance bars supporting said superstructure and extending rearwardly from said plow nose outside of the line of the side members of the truck frame and defining lateral frame members disposed outwardly of the truck wheels and within which the truck frame is adapted to be enclosed, a pair of vertically disposed anchoring members carried by said balance bars, a cross member adjustably attachable to said anchoring members at various selected heights vertically thereof, a pair of vertically disposed attaching members mounted on the truck frame, a pair of laterally extending longitudinally extensible link members pivotally connected at their inner ends to said attaching members on the truck frame and at their outer ends to the balance bars, and a pair of suspension members pivoted at their upper ends to said attaching members on the truck frame and at their lower ends carrying said cross member. 130
13. In a snow plow having mold boards, wings, and a superstructure, a truck frame connected at its forward end to said mold boards, a pair of spaced balance bars supporting said superstructure and extending rearwardly from the mold boards outside of the line of the side members of the truck frame and defining lateral frame members disposed outwardly of the truck wheels and within which the truck frame is adapted to be enclosed, means adjustably connecting said balance bars with the rear end of said truck frame, and means for adjustably mounting the rear ends of said wings on said balance bars and for taking up the thrust of said wings, comprising slides mounted for vertical travel on said superstructure, and push arms disposed between said slides and wings. 135
14. In a snow plow having mold boards, wings, and a superstructure, a truck frame connected at its forward end to said mold boards, a pair of spaced balance bars supporting said superstructure and extending rearwardly from the mold boards outside of the line of the side members of the truck frame and defining lateral frame members disposed outwardly of the truck wheels and within which the truck frame is adapted to be enclosed, means adjustably connecting said balance bars with the rear end of said truck frame, and means for adjustably mounting the rear ends of said wings on said balance bars and for taking up the thrust of said wings, comprising slides mounted for vertical travel on said superstructure, and push arms disposed between said slides and wings. 140
15. In a snow plow having mold boards, wings, and a superstructure, a truck frame connected at its forward end to said mold boards, a pair of spaced balance bars supporting said superstructure and extending rearwardly from the mold boards outside of the line of the side members of the truck frame and defining lateral frame members disposed outwardly of the truck wheels and within which the truck frame is adapted to be enclosed, means adjustably connecting said balance bars with the rear end of said truck frame, and means for adjustably mounting the rear ends of said wings on said balance bars and for taking up the thrust of said wings, comprising slides mounted for vertical travel on said superstructure, and push arms disposed between said slides and wings. 145
